UNITED STATES PATENT OFFICE.

WALTER WHIPPLE AND GUSTAF W. EKDAHL, OF NASHUA, NEW HAMPSHIRE,
ASSIGNORS TO NASHUA MANUFACTURING COMPANY, OF NASHUA, NEW
HAMPSHIRE, A CORPORATION OF NEW HAMPSHIRE.

CARDING MACHINE.

Application filed July 26, 1921. Serial No. 487,581.

To all whom it may concern:

Be it known that we, WALTER WHIPPLE and GUSTAF W. EKDAHL, citizens of the United States, residing at Nashua, in the 5 county of Hillsborough and State of New Hampshire, have invented certain new and useful Improvements in Carding Machines, of which the following is a specification.

In the manufacture of certain textile fabrics, particularly blankets and other heavily napped goods, it has been found that superior results can be produced by using a core yarn for the warp or weft, or both. This yarn consists of a thread, which forms 10 the core, and a covering of fibrous material, usually a sliver, slubbing or roving twisted rather loosely about the thread.

It has been the usual practice heretofore to make this core yarn by first making a sliver, roving, or the like, and subsequently associating the sliver with a reinforcing thread and twisting them together. This process, however, is open to the objection that the sliver is very likely to 15 break while being fed to the twisting devices and thus leave a length of bare thread, which, when woven into the goods, will produce a thin place in the fabric. It is open to the further objection that the thread frequently becomes kinked during the process 20 of twisting, and this kinked portion shows up very plainly in the woven fabric, particularly if the reinforcing thread is of a different color from the sliver.

It has also been proposed heretofore to associate the sliver and reinforcing thread in the carding machine in which the sliver is formed and this process has important advantages over the process just described. 25 It has not, however, gone into use to any substantial extent, so far as we have been able to learn, notwithstanding the fact that this process was proposed many years ago. The reason for this appears to be due largely, 30 if not entirely, to the unsatisfactory nature of the machinery heretofore proposed for carrying out this process. That is, the machinery has been such that there was great liability of the reinforcing threads breaking, 35 and the number of threads that must be handled by a given machine is so great that such breakage necessarily results in a very

serious reduction in the output of the machine. Furthermore, the matter of threading in a broken end is very troublesome in 55 machines of this character.

The present invention has for its general object to improve machines of this character with a view to overcoming the difficulties experienced with these prior machines and producing core yarn of a more uniform quality than that produced by the machinery heretofore available. The invention also aims to devise a mechanism for associating the core and sliver which shall be thoroughly reliable 60 in operation, convenient to use, economical to manufacture, in which wear and depreciation shall be reduced to a minimum, and which shall generally meet the practical requirements of machines of this character. 65

The preferred embodiment of the invention involves a carding machine equipped with mechanism which associates the core thread with the roving before these parts enter the rub belts of the carding machine. 70

The nature of the invention will be readily understood from the following description when read in connection with the accompanying drawings, and the novel features will be particularly pointed out in the ap- 75 pended claims.

Referring now to the drawings,

Figure 1 is a perspective view showing certain parts of a carding machine, modified, however, to include mechanism embodying the present invention; 80

Fig. 2 is a diagrammatic view showing the manner in which the core thread and roving are associated and subsequently handled in the machine shown in Fig. 1; and 85

Fig. 3 is a front elevation of portions of the takeoff rolls of the carding machine, showing the manner in which the core threads are guided between these rolls. 90

Referring particularly to Fig. 2, the main 95 carding roll is designated at 2, the doffer at 3, and the upper and lower takeoff rolls at 4 and 5, respectively. The sheet 6 of carded material travels from the carding roll 2 between the takeoff rolls 4 and 5 where it is 100 split into strips by the upper and lower tapes 7 and 8, respectively. In Fig. 2, the path of travel of the upper set of tapes is indicated by the dotted arrows, and that of the lower

tapes is indicated by the full line arrows. It will be seen from this figure that the strips of carded stock carried by the tapes 8 are transferred to an upper set of rub belts 9, while those carried by the tapes 7 are delivered between a lower set of rub belts 10. These rub belts are given both a rotary and reciprocating movement, as is well understood by those skilled in this art, and they 10 work these strips of carded material into a sliver. The strands of sliver emerging from the upper rub belts 9 are divided, respectively, certain of these strands 11 passing over a spool drum 14 and being wound on 15 a jack spool 15 that rests on this drum, while the alternate strands 12 pass over a drum 16 and are wound on a jack spool 17. The lower strands of sliver 18 and 19 are handled in the same way, being guided, respectively, over drums 20 and 21 and wound on spools 22 and 23. The drums 14, 16, 20 and 21 are driven at the same peripheral speed as the takeoff rolls 4 and 5 which drive the tapes 7 and 8, and the strands of sliver 25 are wound in the various jack spools above mentioned by the contact with their respective drums.

The construction so far described is that of a carding machine well known in the textile industry.

The thread which is to form the reinforcement or core of the composite yarn is shown at 25 wound on a beam 26. This thread body 25 rests on the surface of a drum 27 35 having shafts projecting from its opposite ends which are supported in suitable bearing brackets mounted on the machine frame. In Fig. 1, one of these shafts is designated at 28 and its supporting bracket is shown at 40 29. As the individual strands T of thread are unwound from this thread body, and the diameter of the body is correspondingly reduced, the axis of rotation of the beam 26 will drop, and for this reason the beam is 45 guided by short shafts projecting axially at opposite ends thereof and working in vertical slots formed in stationary brackets. This construction at one end of the beam is shown in Fig. 1, the shaft being shown at 30 50 extending through a vertical slot 31 formed in a bracket 32 which is secured to the frame of the carding machine, and this construction is duplicated at the opposite side of the machine. The drum 27 has a belt connection 55 34, Fig. 2, with the driving shaft 35 of the drum 14, and this connection is of such a ratio that it drives the drum 27 at the same peripheral speed as the drum 14 and the takeoff rolls 4 and 5.

60 The individual strands T of reinforcing thread are led between guides 36 on a stationary bar 37 down to and between similar guides 38 on a traverse bar 39. This bar is mounted horizontally immediately in 65 front of the upper takeoff roll 4 and is sup-

ported in brackets 40 and 41, respectively. For the purpose of giving this bar its traverse movement, a block 42 is secured thereto and is connected by a link 43 with a pin or bolt 44 which projects from a slide 45 70 that is secured by two screws 46 to the front face of a bevel gear 47. This gear is mounted on a stub shaft secured in the machine frame and it meshes with another bevel gear 48 secured to the back of a pinion 49 which 75 is driven by a pinion 50 secured fast to the rear face of a grooved pulley 51. A belt 52 connects this pulley with another pulley 53 secured fast to the shaft 28 that supports one end of the roll 27. The traverse motion 80 of the bar 39 is very short, being simply sufficient to guide the strands T of reinforcing thread backward and forward laterally across the faces of the respective tapes and thus to avoid any localization of the wear of 85 the threads on the tapes. The length of this traverse movement can be varied at will by adjusting the plate 45 on the face of the gear 47 to change the eccentricity of the bolt 44, this adjustment being permitted by the fact 90 that the screws 46 project through slots in the plate 45.

The threads T travel through the rub belts with the strips of carded stock, this stock being rolled loosely about the threads 95 by the action of the belts, and the composite strands thus formed are wound on the jack spools 15, 17, 22 and 23. Subsequently these spools are transferred to other machines where the strands are unwound and twisted 100 to form the core yarn that is used in weaving fabrics.

It will be evident that this construction relieves the reinforcing threads, which are relatively fine, from any substantial strain, 105 the threads being unwound from the beam 25 by the roll 27 at the same rate at which they are advanced by the tapes 7 and 8 and the rub belts 9 and 10, and are wound up on the jack spools. By associating the core 110 thread with the sliver in the manner here described, the liability of breaking one strand or the other of this material is substantially eliminated and we have been able, therefore, to produce in this manner a core 115 yarn of far more uniform quality than by the machinery heretofore available.

It will also be observed that all the parts of the thread handling mechanism are readily accessible and that the mechanism is so 120 organized that access to individual threads is made as easy as can be considering the nature of the carding instrumentalities. In other words, access to the threads is impeded as little as possible by the elements of 125 the thread handling mechanism. The traverse of the threads over the tapes distributes the wear uniformly over the surfaces of these parts so that the surfaces of the tapes are always maintained in proper condi- 130

tion, the presence of ridges or grooves being avoided by this distribution of wear. The beam 26 may be easily removed when it becomes necessary to replenish the supply of 5 thread, and the supporting of the thread supply in this manner has the very important advantage that the beam will hold sufficient thread to run the machine for an entire day so that it is necessary to thread up only 10 once a day.

Having thus described our invention, what we desire to claim as new is:

1. In a carding machine, the combination with carding instrumentalities including devices for splitting the carded sheet of material into strips and rub belts for working said strips of carded material into strands of sliver, of a beam positioned above said beam 15 and holding a supply of thread, means for guiding individual strands 20 of thread from said supply to points where they become associated, respectively, with said strips of carded material on said devices and travel with said strips through the rub belts, said guiding means including 25 a traverse bar and operating means for said bar, said bar being positioned and arranged to move said strands of thread backward and forward at the points where they come in contact with their respective strips 30 of carded material, and mechanism for driving said beam at a speed to unwind said strands of thread therefrom at substantially the same rate at which said strands are fed through said belts.

35 2. In a carding machine, the combination with carding instrumentalities including upper and lower take-off rolls, and a series of tapes supported on said rolls for splitting the carded sheet of material into strips, of 40 a beam positioned above said instrumentalities and holding a supply of thread, a supporting roll on the periphery of which the thread body on said beam rests, a traverse bar in front of the upper of said take-off rolls having devices for guiding individual strands of thread led from said supply into contact with the respective strips of carded material carried by said tapes, and mechanism for reciprocating said traverse bar to guide said strands of thread 45 backward and forward laterally over the surfaces of the respective tapes.

3. In a carding machine, the combination with carding instrumentalities including upper and lower take-off rolls, and a series of tapes supported on said rolls for splitting the carded sheet of material into strips, of a beam positioned above said instrumentalities and holding a supply of thread, a 55 supporting roll on the periphery of which the thread body on said beam rests, a traverse bar in front of the upper of said take-off rolls having devices for guiding individual strands of thread led from said supply into contact with the respective strips 60 of carded material carried by said tapes, means for driving said supporting roll at

of carded material carried by said tapes, mechanism for reciprocating said traverse bar to guide said strands of thread backward and forward laterally over the surfaces of the respective tapes, and means for driving said supporting roll at substantially the same peripheral speed as said tapes travel. 70

4. In a carding machine, the combination with carding instrumentalities including upper and lower take-off rolls, and a series of tapes supported on said rolls for splitting the carded sheet of material into strips, of a beam positioned above said instrumentalities and holding a supply of thread, a 75 supporting roll on the periphery of which the thread body on said beam rests, a traverse bar in front of the upper of said take-off rolls having devices for guiding individual strands of thread led from said supply into contact with the respective strips of carded material carried by said tapes, means for driving said supporting roll at substantially the same peripheral speed as said tapes travel, and connections between said 80 supporting roll and one of said rolls for longitudinally reciprocating said bar to guide said strands of thread backward and forward laterally over the surfaces of the respective tapes. 85

5. In a carding machine, the combination with carding instrumentalities including upper and lower take-off rolls, and a series of tapes supported on said rolls for splitting the carded sheet of material into strips, of a beam positioned above said instrumentalities and holding a supply of thread, a supporting roll on the periphery of which the thread body on said beam rests, a traverse bar in front of the upper of said take-off rolls having devices for guiding individual strands of thread led from said supply into contact with the respective strips of carded material carried by said tapes, means for driving said supporting roll, and connections between said supporting roll and said traverse bar for reciprocating said traverse bar longitudinally to guide said strands of thread backward and forward laterally over the surfaces of said tapes. 95 100 105 110 115

6. In a carding machine, the combination with carding instrumentalities including upper and lower take-off rolls, and a series of tapes supported on said rolls for splitting the carded sheet of material into strips, of a beam positioned above said instrumentalities and holding a supply of thread, a supporting roll on the periphery of which the thread body on said beam rests, a traverse bar in front of the upper of said take-off rolls having devices for guiding individual strands of thread led from said supply into contact with the respective strips of carded material carried by said tapes, means for driving said supporting roll at 120 125 130

substantially the same peripheral speed as
said tapes travel, connections between said
bar and one of said rolls for longitudinally
reciprocating said bar to guide said strands
5 of thread backward and forward laterally
over the surfaces of the respective tapes,
said connections including a crank, gearing

for driving said crank, and an adjustable
connection between said crank and gearing
for varying at will the length of stroke of 10
said traverse bar.

WALTER WHIPPLE.
